UNITED STATES PATENT OFFICE

102,677

DESIGN FOR TEXTILE FABRIC OR SIMILAR ARTICLE

Elsie J. Das, Honolulu, Territory of Hawaii

Application September 28, 1936, Serial No. 65,040

Term of patent 3½ years

To all whom it may concern:

Be it known that I, Elsie J. Das, a citizen of the United States of America, residing at Honolulu, Territory of Hawaii, have invented a new, original, and ornamental Design for Textile Fabric or Similar Article, of which the following is a specification, reference being had to the accompanying drawing, forming a part thereof.

The figure is a view in elevation of the design, which shows the full width of the fabric on a reduced scale.

I claim:

The ornamental design for textile fabric or similar article, as shown and described.

ELsie J. Das.
